UNITED STATES PATENT OFFICE.

ETHEL TAUNTON, OF NEW YORK, N. Y.

DESIGN FOR A PAPER SEAL-WAFER.

40,661.

Specification for Design.

Patented Apr. 26, 1910.

Application filed January 22, 1910. Serial No. 539,625. Term of patent 14 years.

To all whom it may concern:

Be it known that I, ETHEL TAUNTON, a subject of the King of England, residing in the city of New York, county of New York, and State of New York, have invented a new, original, and ornamental Design for Paper Seal-Wafers, of which the following is a specification, reference being had to the accompanying drawing, forming a part thereof.

The figure is a plan view of a paper seal wafer, showing my new design.

I claim:

The ornamental design for a paper seal wafer, as shown.

ETHEL TAUNTON.
